UNITED STATES PATENT OFFICE.

HENRY L. PALMER, OF BROOKLYN, NEW YORK.

DESIGN FOR BASES OR SUPPORTS FOR GLASSES, &c.

SPECIFICATION forming part of Design No. 11,685, dated March 16, 1880.

Application filed February 24, 1880. Term of patent 7 years.

To all whom it may concern:

Be it known that I, HENRY L. PALMER, of Brooklyn, county of Kings, and State of New York, have invented and produced a new and original Design for Bases or Supports for Glasses and other Articles, of which the following is a specification, reference being had to the accompanying drawings, and to the letters of reference marked thereon.

10 Figure 1 is a perspective view of the base with the mug or glass omitted. Fig. 2 is a reverse view of same; and Fig. 3 is an axial section, indicating clearly the form and outline which is in accordance with my design.

15 Like letters, wherever they occur, indicate corresponding parts in all the figures.

My invention has relation to such articles as are ordinarily used in restaurants, at soda-water fountains, and the like, for placing under the glasses, being so formed as to catch the drip or overflow, and are generally placed upon tables or counters, &c.; but the design is likewise applicable to rests, bases, or supports for vases, lamps, and many other articles, 25 as will hereinafter be explained.

The rests A are preferably made of bright metal, so as to present a pleasing contrast with the darkened table or counter and a harmony with the usual bright-metal fittings of the 30 soda-water apparatus or bar-fixtures; but dull metal or colored metal might be employed, if desired. This metal is spun over a filling-block, C, of any material, (preferably wood,) which may be round, oval, or other contour in 35 plan, and of sufficient thickness to afford an appearance of stability and firmness, while at the same time it elevates the article supported a little distance above the surface upon which the rest is placed; and this covering-metal is 40 carried above the upper surface of the block, as at c, forming then an ornamental ridge, which surrounds the flat top of the rest D, giving the structure an appearance of having a considerable pocket or depression for the reception of the article.

The peculiar formation of the ridge, or the curves and planes of which it is composed, as shown in the drawings, might be slightly varied without departing from the principle of my 50 design; but the peculiar formation shown is preferred on account of its neatness and its

general adaptability for the articles with which it is intended to be used.

As exposed beneath the glass, &c., the rest does not indicate its construction, since the 55 edge of the covering-metal is then concealed beneath the block C. The metal from this point is projected upwardly, slightly inclined toward the center in the form of a truncated cone, then molded into the elevated border c, 60 which is composed of an outer and inner curve, joined by a reversed curve at top, and then extends across and covers the upper plane of the rest in a flat surface.

When exposed for sale in the stores, &c., the 65 rest or support may present an appearance substantially as indicated in Fig. 3, the block C being surrounded by a narrow rim of bright or other metal, as at d.

The rests or supports are, of course, intended 70 to be used in sets; but the number in each set is variable according to circumstances, and is an immaterial feature of the invention, since it is proposed to use one or any number of the supports at pleasure.

There are mechanical functions of the rests 75 or supports, as well as mechanical features of construction, not necessary to be detailed herein, and forming no part hereof. For these mechanical features application for mechanical patent will be duly filed.

Aside from the uses named for the rest or support thus designed, it is applicable in many other places or situations than upon the counter or table, and it is intended to cover the design 85 shown herein irrespective of the uses to which the article may be put.

It would be impossible to specify all the uses in which the design may appear to advantage but in order to indicate its scope I will mention that it may be applied as a support for all kinds of drinking-glasses, &c.; as a support for many ornamental articles having small bases; in connection with the feet of many articles of furniture, such as tables, pianos, chairs, desks, easels, especially under the feet of such as have casters or rollers, and under all such as have feet of comparatively small circumference; and, generally, in situations where an ornamental base or support of this 100 character may be found desirable.

When fashioned in the manner above ex-

(OVER)

plained, or in any manner substantially in accordance with the foregoing description, my design affords a graceful outline and generally attractive, artistic, and tasty appearance.

5 Having thus fully described my design, what I claim as new, and desire to secure by Letters Patent, is—

1. The herein-described design for rests or supports or bases, the same being composed 10 of the plain conical edge, the elevated and molded border, and the interiorly-located flat surface, presenting an appearance substantially as shown.

2. In the herein-described design, the plain exterior edge or wall, the curved molded bead 15 or rim *c*, the interior flat portion *D*, and the under-turned or concealed edge *d*, all assembled to present an appearance substantially as indicated in the drawings.

In testimony that I claim the foregoing I 20 have hereunto set my hand.

HENRY L. PALMER.

In presence of—

S. W. HOLCOMB,
WORTH OSGOOD.
